Frank H. Shulley

ATTORNEY

UNITED STATES PATENT OFFICE.

AMBROSE RYDER, OF NEW YORK, N. Y.

TENNIS RACKET.

Application filed May 26, 1921. Serial No. 472,679.

To all whom it may concern:

Be it known that AMBROSE RYDER, a citizen of the United States, and resident of New York city, in the county of New York and State of New York, has invented certain new and useful Improvements in Tennis Rackets, of which the following is a specification.

My invention relates to tennis rackets and the object of my invention is to provide a racket having a web or mesh with means for controlling the degree of tension thereof in the frame. A further object is to provide a web that is adapted to fit in the hoop or frame of the racket and that may be made and sold as an independent article of manufacture.

A further object is to provide a new type of frame adapted to hold the web of the racket firmly and to resist the destructive effect of atmosphere changes to a greater degree than those now generally in use that are made of wood.

A further object is to provide a web that will resist the injurious effects due to moisture in a greater degree than the cat gut webbing now so generally used.

Further objects and the advantages of the improved construction will be described and pointed out in the claims.

Referring to the drawings which form a part of this specification,

Figure 1 is a plan view of a racket embodying my invention.

Figure 2 is a longitudinal sectional view thereof taken on line 2—2 of Figure 1.

Figure 3 is a plan view showing a portion of a racket, and illustrating a modified construction.

Figure 4 is a cross sectional view through the frame of the construction shown in Figure 3 taken on line 4—4 thereof.

Figure 5 is a plan view of a portion of a racket illustrating another modified form.

Figure 6 is a longitudinal sectional view taken on line 6—6 of Figure 5.

Figure 7 is a cross sectional view on an enlarged scale of the frame illustrated in Figure 6.

One of the fundamental features of my invention is that of elastic means for tensioning the web and this means may consist of metal springs formed of steel or other suitable metal or may be provided by the employment of a pneumatic tube. Referring to Figures 1 and 2, A, indicates the

handle of a racket to which is attached a yoke A' which supports an elliptical frame or hoop B made of suitable metal, preferably of an alloy of aluminum in order to provide a frame light in weight, and having a cross-section of the form illustrated at B', which provides an annular groove C' and an inwardly extending edge C hereinafter referred to as a flange and which serves to hold the lower hook ends of the bands D—D etc. each of which is provided with a hook at each end, one held by the flange C and the other attached to the wire frame E which in turn supports the web F. The form of this frame provides an annular groove G in which rests a pneumatic tube H having a valve I through which it may be inflated. The web may be permanently connected to the wire frame E if desired but I prefer to provide small hooks J—J etc. the shanks of which are connected to the web and the hooks detachably connected to the wire frame E as illustrated. A band K of metal or other suitable material is formed to conform to the shape of the tube H and is held thereto by the bands D—D located at this end of the racket, and serves to protect the tube from injury in case the racket strikes the ground in the act of playing. The web F may be made of braided strands or woven of metal, preferably of an aluminum alloy that is light in weight and will not rust or be easily affected by water or bad weather conditions. The frame and yoke are riveted together as illustrated at L and the yoke is provided with a recess M to permit the tube H to fit into the frame as shown. Inflating the tube by air pressure causes an outward movement of its outer periphery which in turn carries the bands outward relative to the frame B and wire frame E, causing a tension in the wire frame and web as will be readily understood.

Referring to Figure 3, it will be seen that the yoke A² is connected to a tubular metal frame B² and a pneumatic tube is connected thereto by bands N—N etc. and held on the inner side of the frame instead of on the outer side thereof as illustrated in Figure 1.

A set of bands D'—D' etc. extend from the wire frame E around the tube H' and when this tube is expanded the web F is drawn taut thereby. A further feature is that two webs indicated by F and F' respectively may be used so that either side of the racket may be used and will present the

same effective working area, the plane extending practically unbroken up to the frame B².

Referring to the construction illustrated in Figures 5, 6 and 7, the handle A is connected to a yoke secured to a semicircular metal frame B³ having inwardly turned edges forming flanges O—O respectively which extend entirely around the frame and are bent to form annular grooves P—P respectively in which the ends of metal springs Q—Q etc. rest. To each spring Q is connected a turnbuckle R by means of which the web F is drawn taut.

By making the racket of metal I eliminate the wood which warps and the web which breaks. A game of tennis may be played on a rainy day without injury to the racket or impairment of its efficiency while playing and also the racket is more durable than when constructed of wood and gut.

Having thus described my invention I claim as new;

1. A tennis racket comprising a frame and a web formed independent thereof and pneumatic means supported by the frame and a plurality of independent bands holding said web to said frame under tension.

2. A tennis racket comprising a frame and a metal web formed independent thereof and pneumatic means supported by the frame and adapted to be connected with and hold said web to said frame under tension.

3. A tennis racket comprising a metal frame, a handle and a yoke connected at one side only to said frame to provide a recess, and a pneumatic tube located in said recess.

4. A tennis racket comprising a frame, a web formed independent of the frame and pneumatic means carried by the frame and supporting the web and embodying elements by means of which the tension of the web may be controlled.

5. A tennis racket comprising a metal frame, a handle and a bifurcated yoke attached to said handle and connected with said frame at one side only.

6. A tennis racket comprising a frame and a web formed independent of the frame and

pneumatic means encircling the web and adapted to hold it under tension in said frame.

7. A tennis racket comprising a frame and a web and pneumatic means for holding said web under tension in said frame said means and web being bodily detachable from said frame.

8. A tennis racket comprising a frame and a web and a pneumatic tube carried by the frame and encircling the web and bands extending from the web to the tube to support the web under tension in the frame.

9. A tennis racket comprising a frame and an independent web and pneumatic means for holding said web under tension in said frame.

10. A tennis racket comprising a metal frame, a web formed independent thereof supported therein, pneumatic means carried by said frame and independent bands connecting said pneumatic means to said web.

11. A racket comprising a metal frame and a handle therefor, and a web located at one side of the frame and in a plane with the face surface thereof, and pneumatic means carried by the frame which act to hold said webs under tension.

12. A racket comprising a frame and a handle therefor, a web having a wire frame and a number of detachable bands which extend over the frame and engage the wire frame of the web.

13. A racket comprising a frame and a handle therefor, a web having a wire frame, a pneumatic means carried by the frame and a number of independent detachable bands which extend over said pneumatic means and the frame and engaging the wire of the web.

14. A racket comprising a frame and a handle therefor, a web having a wire frame and a number of detachable bands having hooks which engage the wire frame of the web.

Signed at New York in the county of New York and State of New York this 24th day of May A. D. 1921.

AMBROSE RYDER.
